ATTORNEY

UNITED STATES PATENT OFFICE

FREDERICK G. JELLISON, OF GEORGETOWN, MASSACHUSETTS

MORTAR AND PESTLE

Application filed November 5, 1928. Serial No. 317,318.

My present invention has reference to a motor operated mortar and pestle for amalgamating and reducing dental or medicinal materials to a powder, the primary object being to provide a device for this purpose that shall be of an extremely simple construction, cheaply manufactured and which will operate in precisely the same manner as were the device hand operated.

10 To the attainment of the foregoing and other objects which will present themselves as the nature of the invention is better understood, the improvement consists in the invention hereinafter described and definitely 15 claimed.

In the drawings:

Figure 1 is a substantially central longitudinal vertical sectional view through the improvement.

20 Figure 2 is an elevation thereof.

Figure 3 is a detail sectional view showing the mortar turned to a position different than that disclosed by Figure 1.

25 Figure 4 is a perspective view looking toward the under face of the mortar.

Figure 5 is a perspective view of the shaft to which the mortar is removably attached.

As disclosed by the drawings I make use of a hollow base 1. Both the top and bottom of 30 the base are preferably partly open and the open top is closed by a plate 2 that is secured thereon by screws or the like. This plate 2 also supports thereon an electrically operated motor 3. Neither the wiring nor the details

35 of the motor have been illustrated as the same may be of any well known construction. The shaft 4 of the motor has fixed thereon a pinion 5 which is received in the hollow base 1 and this pinion is in mesh with a gear wheel 6 that has its upper face centrally contacted by a depending boss 7 formed with the plate 2. The center of the gear wheel 6 is provided

40 with a square or rectangular opening to receive the square or rectangular lug 8 on a shaft 9. From the lug 8 the shaft 9 is provided with a threaded extension 10 which also passes through the gear wheel 6 and has screwed thereon a nut 11. The shaft 9 has a round head 12 which is received in a round

45 depression in the outer face of the plate 2

and from the head the said shaft is formed with a substantially rectangular lug 13.

The lug 13 is designed to be received in a rectangular socket 14 in the closed base of a tubular mortar 15. The mortar has its inner 55 wall inclined downwardly from two of its opposite sides, as indicated by the numeral 15'.

Arranged around the casing of the motor 3 there is a strap 16 to whose outer end there is 60 fixedly secured a sleeve or like tubular member 17. The upper end of the member 17 is closed but the lower end is open. The sleeve or tubular member 17 on its outer face is provided with an elongated slot 18. The sleeve is designed to have received therein one 65 end of the cross sectionally rounded pestle 19.

A threaded and headed element 20 has its shank passed through the slot 18 and screwed in an opening in the pestle. The pestle is normally influenced in a downward direction by 70 a spring 21 that is received in the sleeve or tubular member 17. The lower portion of the pestle is freely received in the mortar 15 and the lower or outer end of the said pestle has

75 two of its opposite sides, cut at angles to present a sharpened end, said angle walls being indicated by the numeral 22. The active or lower end of the pestle is also formed with any desired number of angularly disposed grooves 23, the object being that the walls of 80 the said grooves contact with the material to be powdered in the mortar.

It will be apparent that when the motor is 85 operated the mortar will be rotated by the turning of the shaft 9. Because of the angle lower walls 15' of the mortar it will be seen that each revolution thereof will cause the angle faces 22 on the ends of the pestle to be raised against the pressure of the spring 21 and when the angle lower walls of the said 90 pestle aline or are brought opposite the angle walls 15' of the mortar the springs 21 will force the pestle downwardly into the mortar. The result is that the material will be finely ground or amalgamated in an easy, quick and

95 thoroughly effective manner. The element 20 will prevent the turning of the pestle and when the material is ground in the mortar the outer or headed end 24 of the said element 100 provides a hand hold whereby the pestle

may be raised in the sleeve or tubular member 17 out of the mortar and the mortar as previously inferred may be readily removed from its connection with the lug 13 on the shaft 9.

5 The construction, operation and advantages of my improvement will, it is thought, be understood and appreciated so that further detail description will not be required but obviously I do not wish to be restricted to 10 the precise details herein set forth and, therefore, hold myself entitled to make such changes therefrom as fairly fall within the scope of what I claim.

Having described the invention, I claim:

15 1. A mortar having its lower wall cut angularly from two of its opposite sides to its end, a pestle designed to be freely received in the mortar and having its active end cut angularly from two of its opposite sides, 20 spring means influencing the pestle into the mortar, means for holding the pestle from turning and means for rotating the mortar.

25 2. A mortar having its lower wall cut at a downward angle from two of its sides to the center thereof, a pestle to be received in the mortar and having its active end cut at downward angles from two of its opposite sides to the center thereof, said pestle, from 30 its said end, having angle grooves in the outer face thereof, spring means influencing the pestle in the direction of the mortar, means holding the pestle from turning and likewise permitting the pestle to be moved against the 35 pressure of the spring means out of the mortar, and a motor driven shaft removably connected to the bottom of the mortar.

40 3. In a device for the purpose set forth, a hollow base supporting a motor thereon, gears driven by the motor, a headed shaft centrally journaled through the top of the base and removably fixed to one of the gears and having a substantially rectangular lug on the top thereof, a mortar having a substantially rectangular notch to receive the lug of the shaft therein, said mortar having its 45 inner wall, from two of its opposite sides inclined downwardly to the center, a sleeve supported by the mortar casing and having an elongated slot therethrough, a pestle having one end received in the sleeve and its other end designed to be received in the mortar, said last mentioned end of the pestle being 50 cut at a downward angle from two of its opposite sides and having its outer face, from its said end grooved angularly, a handle element having a shank passing through the slot in the sleeve and entering the pestle and a spring in the sleeve contacting with the pestle to 55 urge the same into the mortar.

60 In testimony whereof I affix my signature.
FREDERICK G. JELLISON.
